UNITED STATES PATENT OFFICE

JOHN IRA FRANK, OF BALTIMORE, MARYLAND, ASSIGNOR OF ONE-HALF TO THEODORE W. SMITH, OF BALTIMORE, MARYLAND

MAGAZINE FOR AUTOMATIC SHOTGUNS

Application filed March 20, 1931. Serial No. 524,166.

My invention relates to improvements in magazines for automatic shot-guns in which the recoil following the explosion of the shell is utilized to effect an operation of the breech mechanism.

6 Guns of this class employ a spring-actuated shell-carrier at the inner end of the barrel and the magazine-tube, in which latter the shells are stored, and the shells are fed rearwardly by a spring in the magazine-tube and in reverse order from that in which they were loaded into the tube,—the feeding of the shells in succession taking place after each firing operation.

10 15 The shell-carrier is located at an opening in the under side of the gun frame, and during the loading of the magazine, this shell-carrier must be sprung inwardly by the fingers of the operator as each shell is pushed through the opening past the carrier and into the inner end of the magazine-tube.

To either load or unload the magazine-tube the shell-carrier must be pressed inwardly and this operation frequently results in the 20 operator cutting his fingers, or if wearing gloves, getting the fingers of the gloves caught in the carrier mechanism.

Moreover, loading or unloading shells at the breech into or from the magazine-tube is 25 accompanied by more or less liability of accidentally firing the gun and is also a slow process.

In practically all of the well-known shot-guns now in extensive use, the shell-carrier is 30 of a forked shape and the end of the fork frequently bruises and scrapes the outer surface of the shell during the loading operation. This shell-surface is waterproofed because 35 in rainy weather the shells sometimes get wet and if they get wet at the bruised or scraped places the moisture will work into the fiber and cause the shell to swell in the magazine to such extent that it cannot be fed therethrough and great difficulty is experienced in removing it.

40 By means of my invention the shells are loaded into the gun in such a way that damage to the shell by the forked carrier will not take place and the difficulty above pointed out 45 is avoided.

One object therefore of the present invention is to provide an improved magazine structure for shot-guns of the class referred to by which the shell-carrier need not be taken into consideration by the operator either for loading or unloading purposes, for the reason that the magazine-tube may be loaded or unloaded at the outer end thereof and at a point remote from the shell-carrier.

Another object of the invention is to provide 55 an improved magazine structure for automatic shot-guns whereby the shells may be dropped into place in the outer end of the magazine without contending with spring pressure each time a shell is inserted therein.

A still further object is to provide an improved magazine structure, including outer and inner tubes,—the outer end of the outer tube having an opening, remote from the breech, for the loading or unloading of shells 60 to and from the magazine, and a spring-operated follower that may be withdrawn to a point beyond the outer end of said opening whereby the shells may be slipped into or run from the outer end of the magazine without manipulating a shell-carrier or pumping the shells from the magazine one at a time, and

65 An additional object is to provide an improved magazine structure which may readily be attached to many of the well-known shot-guns now in use without alteration to their mechanisms.

70 With the above, and other objects in view the invention is illustrated in the accompanying drawings, wherein,—

75 Fig. 1 shows a shot-gun in side elevation with my improved magazine structure attached thereto.

80 Fig. 2 illustrates the intermediate portion of the gun on an enlarged scale with a portion thereof in section and with my improved device attached to the outer end of the magazine-tube.

85 Fig. 3 shows the magazine-tube in longitudinal section with my improved device attached to the outer end thereof.

90 Fig. 4 illustrates my improved attachment withdrawn from the outer end of the magazine tube to permit loading or unloading of the shells to or from the same.

Fig. 5 shows a similar view of the attachment, but on a slightly enlarged scale, and with the innermost telescoping member in section, and

5 Fig. 6 illustrates the invention in a slightly modified form with the side shell-opening formed in the magazine-tube itself.

Referring to the drawings, the numeral 10 designates the butt-stock of the gun; 11 the barrel; 12 the receiver; 13 the forearm and 10 14 the magazine tube.

The shell-carrier 15 is located in the receiver 12 and is pivoted at 16 so it may be moved upwardly during the feeding of the 15 shell to the inner or breech-end of the barrel from the magazine tube in the old way, and I propose to leave this carrier as it is but load and unload the magazine tube 14 at the opposite or outer end of the latter.

20 The usual recoil spring 17 is carried around the magazine-tube and the latter is not disturbed by my attachment with the exception of the removal of the usual cap that screws onto the thread 18 at the outer end 25 of the magazine tube and by the withdrawal of the ordinary follower spring from the said tube.

The inner end of the magazine tube terminates in the receiver in front of the free 30 end of the shell-carrier 15 while the outer end of said magazine-tube is externally screw-threaded as at 18.

One embodiment of my improvement is illustrated in Figs. 3, 4 and 5, wherein I 35 show a tubular retainer 19, one end 20 of which is internally threaded so as to screw onto the threads 18 at the outer end of the magazine-tube. This tubular retainer has a contracted outer end which produces an annular interior stop-shoulder 21 around its 40 end opening 22 for a purpose that will presently be explained.

Along one side, the tubular retainer is provided with a longitudinal opening 23 of 45 a size that will permit the free passage of a shell 37.

To the tubular retainer I connect one end 50 of a spring actuated follower whose function is to press the shells rearwardly in the magazine tube 14 so as to feed them successively to the shell-carrier for transfer to the firing position in the receiver in the usual manner. The means for effecting this transfer operation forms no part of my invention 55 and therefore is not illustrated herein.

I prefer to form the shell follower or feed device of a plurality of telescopic sections, and while the number of sections may vary, I show in the present disclosure a series of 60 four of such sections which are designated 24, 25, 26 and 27 respectively.

The outermost follower section 24, as best shown in Fig. 5 is the smallest in diameter and is attached to and projects from a bolt- 65 casing 28 at the inner side of an end cap 29

which closes the outer end of the retainer 19. This cap has a pair of bolts 30 at its inner side so they may engage the inturned stop shoulder 21 around the end opening 22 of the tubular retainer 19 and thereby detachably connect the follower to the outer end of the said tubular retainer. The cap 29 is of such size with respect to the end opening 22 of the tubular retainer that while it may be partly inserted in said opening so as to engage the end of the follower-section 24, it will not pass inwardly through said opening 22. The diameter of said opening 22 is such that not only may the cap be disengaged from the stop shoulder 21 and then drawn out, but the follower tube 24 and the succeeding follower tubes 25, 26, and 27 may all be drawn outwardly through said opening 22 up to a certain point, as will presently be explained.

One end of each follower section is slightly flared outwardly in order that it may engage an interior flange 31 on the next larger follower section, and similar out-turned and in-turned flanges are formed on all of the follower sections so that said sections may all be telescopically connected.

The innermost follower section 27 is the largest in diameter, and near its inner end I provide the same with an exterior annular bead 32 which forms a stop to engage the inturned stop-shoulder 21 around the forward end-opening 22 of the tubular retainer 19 when the telescopic follower is drawn forward from the magazine-tube and also from the said retainer 19 to bring the longitudinal opening 23 of the retainer into direct communication with the magazine tube and permit loading or unloading of shells to or from the magazine tube behind the inner end of the drawn-out follower.

By therefore providing the annular bead 32 on the innermost follower section, I prevent entire withdrawal of the follower device but allow it to be sufficiently withdrawn to uncover the longitudinal shell-opening 23 in the retainer.

The rear end of innermost follower section 27 is closed by a detachable cap 33.

A long coiled spring 34 is inserted in the several follower-sections with its outer end seated against the outer detachable cap 29 and its inner end seated against the inner cap 33.

This spring 34 simply collapses as the sections telescopically slide on each other when restoring the follower in the retainer as the magazine is being filled, and said spring obviously will expand each time a shell is removed from the inner end of the magazine and transferred to firing position so as to feed the remaining shells rearwardly.

It will be noted that the shells are transferred from the magazine to firing position in the same order in which they were loaded 130 into the magazine.

It will also be noted that when loading the shells into the magazine there is no spring to resist the feeding of the shells into place, for at this time, the follower sections will be drawn out and the spring in the follower-sections will be in its fully-expanded condition and beyond the shell feed-opening. Thus loading is simple and unhampered. In unloading, the operation is just as simple, for when the shell-opening 23 is uncovered, the shells may be poured from the front end of the magazine and no pumping operation or spring-pressed shells have to be contended with.

It will further be noted that by means of my attachment the ordinary magazine is extended and an additional shell may be stored in the same gun.

Furthermore, the device is readily attachable to guns now in use and as being manufactured, without alteration of any kind to the gun structure.

In Fig. 6 the invention is shown as applied to the magazine tube itself in that the outer end of the said tube 14 has a longitudinal shell-opening 35 formed directly therein instead of in a retainer at the outer end thereof.

In this modified form I also provide a slot 36 in the under side of the forearm 13 so that a shell 37 may be passed through the slot to the shell-opening 35 when the follower 38 is drawn out sufficiently to uncover that opening 35, and the shells may thus be inserted or withdrawn with respect to the magazine tube.

Also in this modified form, I show the follower 38 as carried in a tube 39 which may be slid into or withdrawn from the magazine tube 14, and this inner tube is of such diameter as to receive the previously-inserted shells as it is moved rearwardly into the loaded magazine tube,—the tube 39 simply passes around the shells as it moves back to the fully-inserted position.

Also in this form, the outer end of the inner tube 39 will carry a cap which will engage the threads 18 on the outer end of the magazine tube.

I claim,—

1. In an automatic shot gun the combination with a barrel, of a magazine tube extending along the side of the barrel, a tubular retainer at the outer end of the magazine tube and having a longitudinal shell opening in its wall, a sectional follower attached to the retainer and extensible on the interior of the magazine tube and means for withdrawing the follower outwardly from one end of the retainer to uncover the longitudinal retainer opening to permit the entrance of shells into the magazine tube.

2. In an automatic shot-gun the combination with a barrel, of a magazine tube extending along the side of the barrel, a tubular retainer detachably connected to the outer

end of the magazine tube and having a longitudinal shell-opening in its wall, a plurality of telescoping tubular sections detachably connected to the retainer and spring means in said telescoping sections to press the latter in a rearward direction in the magazine past the said longitudinal shell-opening.

3. In an automatic shot-gun the combination with the barrel, of a forearm extending along the under side of the barrel, a shell carrier at the inner ends of the barrel and forearm, a magazine extending forwardly through the forearm in front of the shell-carrier and along the barrel said magazine having a longitudinal opening adjacent the outer end of the forearm for the passage of shells to and from the magazine for loading and unloading the latter adjacent said forearm-end and remote from the shell-carrier and yielding telescoping means for feeding the shells rearwardly to the shell-carrier in the same order in which they were loaded through the said longitudinal opening into the magazine.

In testimony whereof I affix my signature. JOHN IRA FRANK.
